US0D1073075S

(12) **United States Design Patent** (10) **Patent No.:** **US D1,073,075 S**
(45) **Date of Patent:** **** Apr. 29, 2025**

(54) **FACE CRADLE OF A THERAPY TABLE**

(71) Applicant: **Aescape, Inc.**, New York, NY (US)

(72) Inventors: **Eric A. Litman**, Brooklyn, NY (US); **Kathleen Lockhart**, Harwich, MA (US); **Daniel Harden**, Carmel, CA (US); **Cole Derby**, Santa Clara, CA (US); **Yale Shaw**, San Francisco, CA (US); **Haiping Liao**, San Francisco, CA (US); **Natalie Rowan**, San Jose, CA (US); **Benjamin Martin**, San Francisco, CA (US)

(73) Assignee: **Aescape, Inc.**, New York, NY (US)

(**) Term: **15 Years**

(21) Appl. No.: **29/849,706**

(22) Filed: **Aug. 12, 2022**

CLAIM

The ornamental design for a face cradle of a therapy table as shown and described.

DESCRIPTION

FIG. 1 is a perspective view of a face cradle of a therapy table showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view thereof taken along line 8-8 in FIG. 6.

The broken lines in the drawings depict environmental subject matter and form no part of the claimed design.

The broken line in the end of the unclaimed area in FIG. 8 depicts symbolic break line. The symbolic break lines and any appearance of the article beyond the symbolic break lines form no part of the claimed design.

1 Claim, 8 Drawing Sheets
